UNITED STATES PATENT OFFICE.

WILLIAM B. FENN, OF NEW YORK, N. Y.

METHOD OF STERILIZING CANNED GOODS.

1,378,531.

Specification of Letters Patent. Patented May 17, 1921.

Application filed July 15, 1920. Serial No. 396,559.

To all whom it may concern:

Be it known that I, WILLIAM B. FENN, a citizen of the United States, residing at New York, in the county and State of New York, 5 have made a certain new and useful Invention in Method of Sterilizing Canned Goods, of which the following is a specification.

This invention relates to a process of sterilizing canned goods such as canned 10 fruits, vegetables, or the like.

The object of the invention is to provide a new process which is simple and economical for commercial use and efficient in operation for sterilizing canned goods.

15 Further objects of the invention will appear more full hereinafter.

The invention consists substantially in the process of treating a can and its contents to sterilize the same, all as will be more fully 20 hereinafter set forth, as shown by the accompanying drawing, and finally pointed out in the appended claims.

Referring to the drawing:

Figure 1 is a diagrammatic view in section of the apparatus employed in one method of carrying out the process of my invention.

Fig. 2 is a diagrammatic view in front elevation, partly broken away, of a modified 30 arrangement of apparatus employed in accordance with my process.

Fig. 3 is a broken detail view showing a modified form of can cover which can be employed in accordance with my process.

35 The same part is designated by the same reference character wherever it occurs throughout the several views.

I have discovered that canned goods can be sterilized in a more simple manner than 40 has heretofore been employed in the canning industry and necessarily a cheaper and more economical manner with the same or greater efficiency and effectiveness in securing perfect sterilization. The exact process of my

45 invention consists in placing a can in a retort, or the like, which is preferably sealed, to form a steam chamber, with the can filled with the material to be sterilized, with some means provided for allowing ingress of the steam within the retort into the can. The steam is supplied to the retort preferably 50 under pressure, and the ingress of the steam from the retort may be effected in any suitable manner, for example, by leaving an opening in some part of the can or by loosely attaching the can cover. In each instance,

however, the can should be placed in the retort in an inverted position or on its side. After the steam has been allowed to thoroughly agitate and sterilize the contents of 60 the can the can is then turned right side up either with the steam under pressure still in the retort or after the steam has been exhausted slowly enough to prevent the liquid in the can from blowing off. The can is then 65 permanently sealed, or in the instances given as examples above, the hole is soldered or otherwise closed up, or the cover is completely crimped on the can. While I am unable to advance the theory as to why this 70 method of sterilizing canned material is more effective than the methods now employed, the fact remains that it has proven to be so, and it is obvious that it is a much more simple process and more economical of 75 carrying out than the processes now employed.

Referring to the drawing, I have illustrated several forms of apparatus employed in utilizing the process of my invention 80 wherein 1 designates the steam retort into which steam is admitted through a pipe line 2, which pipe line is controlled by valve, not shown, in any suitable well known manner. The steam is exhausted from the retort 1 85 through pipe line 3 controlled similarly by valves in any suitable well known manner. The retort is provided with a removable base 4 on which the can is mounted. In the form shown the can 5 is provided with a cover 6 90 loosely attached thereto and the can is inserted in the retort in an inverted position in this instance, although as above set forth it can be placed on its side as well. Steam is admitted through line 2 into the retort a 95 sufficient length of time to thoroughly sterilize the material contained in the can and is then exhausted. The base 4 is then withdrawn and the can righted and the cover completely attached thereto. In place of the 100 loosely applied cover 6 the can 5 may be provided with an opening 7 at any desired point, for example, in the cover 6, which opening may be closed after the can has been righted into its upright position. 105

In Fig. 2 I show one means of carrying my process out where it is desired to simultaneously sterilize a number of cans. In this instance the retort 1 is rotatably mounted between bearings or journal posts 8. The 110 journals in this instance are hollow to admit the steam inlet pipe 2 and the exhaust pipe

3 therethrough. The retort is provided with a removable cover 9 to permit the cans 5 being placed in the retort according to the size of the retort and cans, or as desired. The 5 retort is then placed in an inverted position and steam admitted through the pipe line 2. After the steam has thoroughly agitated the contents of the cans and has approximately equalized the pressure within and without 10 the cans the pressure is exhausted through pipe line 3, the retort rotated to its upright position, the cans removed and completely sealed as above described.

One thing that I have discovered which I 15 believe will tend to explain the phenomenal results obtained by means of the process of my invention is that best results are obtained when the can is completely sealed while steam under pressure is still retained in the 20 respective cans.

Many modifications will occur to those skilled in the art without departing from the spirit and scope of my invention as defined in the claims. Therefore what I claim as 25 new and useful and of my own invention and desire to secure by Letters Patent is,—

1. The process of sterilizing canned goods which consists in placing an unsealed can in a position other than its top-side up 30 position, then subjecting the can and its contents to steam under pressure, so that the steam enters into the can and agitates the contents thereof, then shifting the can to its normal top-side up position, and finally completely sealing the can.

2. The process of sterilizing canned goods which consists in placing an unsealed can in a position other than its top-side up posi-

tion within an inclosed chamber, then admitting steam under pressure into said 40 chamber whereby the steam enters into the can and agitates the contents thereof, then shifting the can to its normal top side up position, and finally completely sealing the 45 can.

3. The process of sterilizing canned goods which consists in placing an unsealed can in a position other than its top-side up position within an inclosed chamber, then admitting steam under pressure into said chamber 50 whereby the steam enters into the can and agitates the contents thereof, then shifting the can to its normal top-side up position, then slowly exhausting the steam under pressure from said chamber, and finally 55 completely sealing the can.

4. The process of sterilizing canned goods which consists in placing an unsealed can in an inverted position within an inclosed chamber, then admitting steam under pressure into the chamber whereby the steam enters into the approximate bottom of the can and rises to the top of the same to agitate the contents thereof, then shifting the can to its top-side position, then exhausting 60 the steam from the chamber slowly so that the liquid contents of the can will not be blown out of the can by the steam within the can due to sudden change of the external pressure on the can, and finally completely 65 sealing the can.

In testimony whereof I have hereunto set my hand on this 13th day of July A. D., 1920.

WILLIAM B. FENN.
